FIG. 1

FIG. 2

FIG. 7

FIG. 3

FIG. 1 is a perspective view of an expansible link chain for a bracelet or the like, showing my new design;

FIG. 2 is a side elevation of the chain illustrated in FIG. 1;

FIG. 3 is a perspective view of the chain shown in FIG. 1, partly expanded, the showing of the grooves or ridges for producing a mat effect and surface shading being omitted on the three left hand links which are shown diagrammatically to illustrate how the links are separated when the chain is expanded;

FIGS. 4, 5 and 6 are sectional views taken on lines 4—4, 5—5 and 6—6 respectively of FIG. 1, the top links only being shown;

FIG. 7 is a longitudinal sectional view of one of the top links taken on line 7—7 of FIG. 1.

The dominant features of my design reside in the portions shown in full lines.

I claim:

The ornamental design for an expansible link chain for a bracelet or the like, as shown and described.
